MEANS FOR INSPECTING GUN BARRELS

Arthur Cyril Webb Aldis, Sparkhill, Birmingham, England, assignor to Aldis Brothers Limited, Sparkhill, Birmingham, England

Application June 19, 1943, Serial No. 491,525
In Great Britain April 14, 1942

8 Claims. (Cl. 88—14)

1

This invention has for its object to provide improved means for inspecting the straightness of the bores of rifle and other gun barrels.

In the accompanying sheets of explanatory drawings

Figure 1 is a side elevation of means constructed in accordance with the invention for inspecting the bores of rifle barrels.

Figures 2 to 6 are views illustrating to a larger scale various parts of the means shown in Figure 1, Figures 2 and 3 being respectively a front elevation and a sectional side elevation of the upper part, Figures 4 and 5 being respectively a front elevation and a sectional side elevation of the lower part, and Figure 6 being a horizontal section on the line 6—6 of Figure 4.

Figure 7 is a plan of a modified detail.

Figures 8 and 9 are sections taken respectively on the lines 8—8 and 9—9 of Figure 7.

Figure 10 is a side elevation of a modified form of the invention.

Figures 11 and 12 are side elevations taken at right angles to each other of another modified form of the invention.

In carrying the invention into effect as shown in Figures 1 to 6, I employ a vertical post *a* which at its lower end is secured to a supporting base *b* adapted to rest on a bench or on the ground, the post and base being conveniently of hollow form. On the upper part of the post *a* is secured a bracket *c*, and on the lower part of the post is secured another bracket *d*, the distance between the two brackets being dependent on the length of the rifle barrels whose bores are to be inspected. The brackets *c*, *d*, respectively carry a pair of hollow centres *f*, *g*, which are arranged coaxially with each other, and by which a rifle barrel (shown in broken lines and indicated by *h*) can be supported in a vertical position, the inner ends of the centres being shaped to a conical or like form so that they can enter and support the adjacent ends of the rifle barrel.

The upper centre *f* is slidably supported by and extends from the lower end of a hollow cylindrical portion *j* of the upper bracket *c*, the upper end of this centre being open and the lower end closed except for an axial orifice *k* of small diameter. The hollow portion *j* of the bracket *c* is closed at its upper end by a glass window *l*, and contains a helical compression spring *m* which by acting on the upper end of the centre *f* tends to hold the latter in its lowermost position. On the upper bracket *c* is mounted a housing *n* for a light source *o* whereby the orifice *k* in the upper centre *f* can be illuminated through the hollow

2

portion *j* of the bracket, the upper centre serving as an opaque mask between the light source and the bore of the rifle barrel *h*. In the example shown the light source *o* has the form of an electric lamp of high intrinsic brightness, and is adjustably mounted in a holder *p* in the housing *n*, the bulb of the lamp being preferably frosted to afford diffused illumination.

The lower centre *g* is open at both its upper and lower ends, and extends through the upper side of the lower bracket *d* which is made to a hollow form. At its outer end the upper side of the lower bracket *d* is formed with a socket *q* in which is secured the lower end of a tubular housing *r*, the arrangement being such that the housing extends from the upper side of the bracket at any convenient inclination away from the post *a*. Supported in and extending from the outer end of the housing *r* is a telescope *s* which at its inner end abuts against an annular shoulder *t* in the socket *q*, the telescope having an eye-piece *u* at its outer end, and an object lens (not shown) in its inner end. In the interior of the lower bracket *d* and near its upper side is mounted a light-deflecting prism *v* whereby the bore of the rifle barrel *h* can be viewed through the telescope *s*, the prism being arranged and adapted to deflect the optical axis of the telescope through the lower centre *g*, and the clear aperture of the object lens in the telescope being larger than the diameter of the barrel bore.

To enable the rifle barrel *h* to be mounted in position between the hollow centres *f*, *g*, the upper centre *f* is moved upwardly against the action of the spring *m*. For effecting this movement a lever *w* is connected by a pivot *x* near one end to the upper bracket *c*, and is shaped at this end to a fork-like form for engaging the under sides of a pair of pins *y* secured to and extending from opposite sides of the upper centre *f*, so that downward movement of the other end of the lever causes the required upward movement of the upper centre, the latter end of the lever being provided with a chain *z* or being otherwise adapted to be actuated by an attendant.

At a position midway between the brackets *c*, *d*, a third bracket *2* is secured on the post *a*, and to this bracket is pivotally connected the centre of a substantially vertical lever *3* having secured to its ends V-shaped supports *4*, *5*, for the adjacent parts of the rifle barrel *h*. The pivot *6* of the lever *3* is situated opposite to the position occupied by the centre of the rifle barrel *h*, and the arrangement is such that when the rifle barrel *h* occupies the position shown the lower support *5*

3

abuts against an adjustable stop 7 on the bracket d, and when the position of the barrel is reversed the upper support 4 abuts against another adjustable stop 7a on the bracket c.

When the rifle barrel h is mounted in position between the centres f, g, there is seen on looking into the eye-piece u of the telescope s, an image of the orifice k in the mask formed by the upper centre f, this image being surrounded by a bright concentric circle, with other larger concentric circles around it.

The inner concentric circle arises from rays which are reflected once from the whole surface of the bore of the rifle barrel h for a distance of two-thirds the length of the barrel measured from the viewing end, (always provided the aperture of the object lens in the telescope s includes the whole diameter of the bore).

If the bore of the rifle barrel h is straight for the whole of this two-thirds length the inner circle is seen as a sharply defined thin line of uniform width, and, furthermore, if the axis of this straight portion accurately passes through the centre of the orifice k, this inner circle is concentric with the image of the orifice. If the said two-thirds length of the barrel is straight but points in a direction out of line with the orifice, then the inner circle will be sharply defined but eccentrically placed with regard to the image of the orifice. If, on the other hand, the said length of the barrel is not straight, the circular image will appear blurred at one or more positions, or will be duplicated eccentrically.

To facilitate location of the position of the deformation in the bore to which the eccentric circle or the blurred appearance of the circular image is attributable, I mount in the interior of the lower bracket d and between the prism v and the lower centre g a transversely movable slide 8 which extends through the inner and outer sides of the bracket, and which has associated with its outer end actuating means in the form of calibrated micrometer mechanism 9 mounted on the bracket. The slide 8 is provided with a straight-edged aperture 10 which is situated beneath the lower centre g, and with another aperture 10a situated between the prism v and the telescope s, the latter aperture being sufficiently large to prevent obstruction by the slide of the light path between the telescope and prism throughout the whole range of movement of the slide. To locate the position of the deformation in the bore of the barrel h the slide 8 is moved in one direction until one of the eccentric circles or the blurred portion of the image is masked by one of the straight edges of the aperture 10, the amount of such movement being readily ascertainable from the micrometer mechanism 9 which may be conveniently calibrated in terms of distances along the barrel. The slide 8 may then be moved in the opposite direction to obtain a similar effect with the opposite straight edge of the aperture 10, the reading thus obtainable from the micrometer calibrations serving as a check on the previous reading.

Having examined the barrel h from one end the position of the barrel can be reversed so that the two-thirds length of the barrel from the opposite end may be similarly scrutinized.

In the case where a deformation is located in the barrel h, suitable means may be brought into operation for applying corrective pressure to the gun barrel, the straightening effect of which can be observed through the telescope s by the narrow-

4

ing down of the blurred portion of the image as the pressure is applied.

In certain cases the viewing telescope s may be provided with a fine scale graticule (not shown) which is seen in the field of view simultaneously with the image of the central orifice k and the circles surrounding it.

The brackets c, d and 2 are axially adjustable on the post a to suit rifle barrels of different lengths, but are prevented from angular movement by rib-like projections 11 on adjacent parts of the post.

To enable the telescope s to be adjusted in a vertical plane about the inner end of its housing r for bringing the required part of the image above described to the centre of the field of view, the housing is of larger diameter than the body part of the telescope, and is provided at its upper end with an adjusting screw 12 and a spring-loaded plunger 13 adapted to act on opposite sides of the said body part, the outer end of the housing being shaped to prevent sideways movement of the telescope. This adjustment enables the corresponding arcs of the second and third concentric circles to be brought under observation for locating bends in the bore of the barrel. These circles arise from rays that have been respectively twice and three times reflected from the bore of the barrel. The adjustable part of the micrometer mechanism is provided with three different scales (not shown) corresponding respectively to the first, second and third circles, and these scales can be observed through three helical windows 9a shown in Figures 1 and 5.

For affording access to the lamp o, its housing n is pivoted at 14 to the lamp holder p which is secured to the upper end of the hollow portion j of the bracket c, a spring-loaded ball or other detent 15 on the lamp holder being adapted by engagement with a recess in the lamp housing to hold the latter in its service position.

Instead of the slide 8 above described I may employ the modification shown in Figures 7 to 9 in which the parts similar or analogous to those above described are indicated by the same reference characters suffixed by "1." In this modification a slide 81 is movable across the hollow bracket d1 by the micrometer mechanism 91 against the action of springs 16, and at right angles to this slide is arranged a second slide 17, the latter being supported by the bracket and movable in any convenient manner. Arranged between and movable by both of the two slides 81, 17 is a third slide 18. The two slides 81, 17 are formed respectively with elongated openings 19, 20 arranged to prevent obstruction by these slides of the light path between the lower centre and prism above described. The third slide 18 is formed with a pair of oppositely arranged D-shaped openings 21 having their straight edges in alignment with each other and parallel with the longitudinal axis of the second slide 17, these openings being arranged to overlap at the adjacent ends so that their aligned edges are separated by a gap as shown. By moving the second slide 17 to bring either of the D-shaped openings 21 opposite to the opening 19 in the slide 81, the straight edge of this D-shaped opening can be used in a similar manner to the corresponding edge of the previously described aperture 10 for locating a deformation in the bore of the barrel. By moving the second slide 17 to an intermediate position a comparison can be made between the effects produced by the straight edges of both D-shaped openings 21.

5

The example shown in Figure 10 is suitable for use in inspecting the bores of gun barrels larger than rifle barrels, and the parts similar or analogous to those above described are indicated by the same reference characters suffixed by "2." In this example, the lamp housing n^2 is mounted on the base b^2 at one side of the post a^2 , and the hollow centre f^2 which serves as the mask is mounted on the lamp housing and may have a rounded upper end. Also the bracket 2^2 carries a V-shaped crutch-like supporting member 22 for the centre of the gun barrel h^2 , this member being adjustable by a hand wheel 23 . Moreover, the other centre g^2 is mounted on a hollow body 24 which is carried by the bracket c^2 through the medium of a parallel motion linkage 25 , the latter being loaded by a strong spring 26 . On the side of the hollow body 24 remote from the linkage 25 is mounted the micrometer mechanism 9^2 , and in this body is mounted the transversely movable slide above described. On the upper side of the hollow body 24 is mounted a chamber 24^a containing the prism v^2 , and from one side of this chamber extends the housing r^2 carrying the telescope s^2 . The hollow body 24 and the parts carried thereby form a unitary structure which can be moved upwardly to enable the gun barrel h^2 to be placed in position. This movement is assisted by the spring 26 which also serves to retain the said unit in its raised position until it is again moved downwards, the arrangement being such that the effect of the spring is reduced as the hollow body 24 is moved downwards and is increased as the body is moved upwards. The base b^2 may be provided with adjustable supporting screws as 27 .

Another possible form of the invention is shown in Figures 11 and 12 in which parts similar or analogous to those above described are indicated by the same reference characters suffixed by "3." In this example the housing r^3 of the telescope is provided at its inner end with an enlargement 28 from one side of which extends the micrometer mechanism 9^3 and which contains the transversely movable slide above described. At the side opposite to the telescope housing r^3 its enlargement 28 is formed or provided with the centre g^3 , the latter being situated coaxially with the telescope s^3 . The lamp housing n^3 is formed or provided with the other centre f^3 which serves as the mask. Both the enlargement 28 of the telescope housing r^3 and the lamp housing n^3 are provided with arms 29 , and are interconnected by tension springs 30 attached to the ends of the arms, the arrangement being such that the springs can lie symmetrically along the sides of the gun barrel h^3 .

Instead of being adapted for use by direct vision, with the eye of the observer placed near the eye-piece, the telescope in any of the examples above described may be adapted to project the image on to a screen situated at a distance from the eye-piece.

By this invention inspection of the straightness of rifle or other gun barrel bores can be carried out in a very expeditious manner and with a minimum of fatigue. Moreover, all the operations can be carried out by artificial light. The invention is not however limited to the examples above described as subordinate details may be varied to suit requirements.

Having thus described my invention what I claim as new and desire to secure by Letters Patent is:

1. Means for inspecting the bore of a rifle or

6

other gun barrel, comprising the combination of a pair of hollow centres arranged coaxially with each other and at a sufficient distance apart to enable the barrel to be mounted between them, one of the centres having a closed end which serves as a mask and has a relatively small axial orifice, optical viewing means associated with the other centre and arranged so that images formed by reflection of the orifice in the bore of the barrel can be inspected, a transversely movable slide arranged in association with the latter centre and the viewing means and operable to ascertain the position of a defect in the said bore by partially obstructing the light path between the associated centre and viewing means, and supporting means whereby the two centres, the optical viewing means, and the slide are supported in the required relationship.

2. Means as claimed in claim 1, in which the supporting means comprise in combination a supporting base, a post on the base, a bracket mounted on the post and carrying the hollow centre forming the mask, a second bracket mounted on the post and carrying the other hollow centre, the optical viewing means, and the transversely movable slide, a third bracket mounted on the post at a position between the first and second brackets, and means on the third bracket for affording lateral support to the barrel.

3. Means as claimed in claim 1, in which the supporting means comprise in combination a supporting base carrying the hollow centre forming the mask, a post on the base, a bracket mounted on the post and carrying the other hollow centre, the optical viewing means, and the transversely movable slide, a second bracket mounted on the post at a position between the base and the first bracket, and means on the second bracket for affording lateral support to the barrel.

4. Means as claimed in claim 1 in which the optical viewing means comprise in combination a telescope, a hollow body on which the telescope is mounted, and a prism arranged in the interior of the hollow body and adapted to deflect the optical axis of the telescope through the adjacent hollow centre, the latter being carried by the said hollow body.

5. Means as claimed in claim 1, in which the supporting means comprise in combination a supporting base, a post on the base, a bracket mounted on the post and carrying the hollow centre forming the mask, a second bracket mounted on the post and carrying the other hollow centre, the optical viewing means, and the transversely movable slide, a third bracket mounted on the post at a position between the first and second brackets, a lever pivoted at a position between its ends to the third bracket, and end pieces on the lever for accommodating adjacent parts of the barrel.

6. Means as claimed in claim 1 and having in combination with the transversely movable slide, a second slide carried by and also movable at right angles to the first mentioned slide, and means for moving the second slide relatively to the first slide, the two slides being formed with apertures through which the bore of the barrel can be inspected, the aperture in the second slide having a pair of parts which are displaced relatively to each other in the direction of movement of the second slide so that by appropriate movement of the second slide either of the said parts can be registered with the adjacent part of the aperture in the first slide, and the two parts of the

aperture in the second slide being formed with and situated at opposite sides of a pair of aligned fault-locating straight edges so arranged that by movement of the second slide relatively to the first slide either of the said edges can be brought to a service position opposite to the aperture in the first slide for the purpose described.

7. Means for inspecting the bore of a rifle or other gun barrel, comprising the combination of a masking member adapted to be mounted at one end of the barrel and having an axial orifice which can be illuminated from any convenient source of light, optical viewing means adapted to be mounted at the other end of the barrel and arranged so that images formed by reflection of the orifice in the bore of the barrel can be inspected, a transversely movable slide arranged in

association with the viewing means and operable to ascertain the position of a defect in the said bore, by partially obstructing the light path between the interior of the barrel and the viewing means, and supporting means whereby the mask, the viewing means, and the slide are supported in the required relationship.

8. Means as claimed in claim 7, in which the supporting means comprise tension springs interconnecting the masking member and the optical viewing means and adapted to lie alongside the barrel so as to hold the said member and optical viewing means in position on the corresponding ends of the barrel, the said viewing means serving to carry the transversely movable slide.

ARTHUR CYRIL WEBB ALDIS.
